M. A. QUIROGA.
EXPLOSION ENGINE.
APPLICATION FILED FEB. 13, 1920.

1,432,900.

Patented Oct. 24, 1922.

UNITED STATES PATENT OFFICE.

MIGUEL ANGEL QUIROGA, OF BUENOS AIRES, ARGENTINA.

EXPLOSION ENGINE.

Application filed February 13, 1920. Serial No. 358,431.

To all whom it may concern:

Be it known that I, MIGUEL ANGEL QUIROGA, citizen of Argentina, and resident of the city of Buenos Aires, Argentina, have 5 invented certain new and useful Improvements in Explosion Engines (for which I have filed an application in Argentina September 2, 1918), of which the following is a specification.

10 This invention refers to the economization of the naphtha or liquid combustible for explosion engines, and has for its object to provide a suitable apparatus for regulating the proportions of the naphtha and the 15 air in the explosive mixture, thus obtaining a notable improvement in the efficiency of such motors, especially those used in automobiles and motor boats.

This object is accomplished by making use 20 of the excess of naphtha which is found in nearly all carburetors, introducing an additional quantity of air in the carbureted gas, thus obtaining the best possible efficiency and at the same time avoiding the deposit 25 of carbon produced by incomplete gas combustion. This amount of air must be increased in proportion to the velocity of the car or of the engine, which in accordance with the invention is effected by a system of 30 perforated disks and a wing or butterfly valve, operated by a crank connected to the accelerator rod, as will be more clearly described in the present specification, and specified in the appended claims.

35 In the accompanying drawings illustrative of a system of construction embodying my invention, Fig. 1 is a view in side elevation, partially in section of the apparatus; Fig. 2 is a front view of the same, showing the apparatus mounted on the intake pipe of an engine; Fig. 3, is a detail of the wing or butterfly valve; Fig. 4 a view of one of the stationary perforated disks, Fig. 5 of the movable disk, and Fig. 6 is a view of a 40 detail of the device.

45 In the said drawings 4 and 5 are the two principal parts of the casing of the apparatus which are held together by a screw which serves at the same time for securing the disk 2 in its position. The front part of the casing piece 4 is provided with openings permitting the admission of air which is controlled by means of the perforated disks 2 and 3 and the wing valve 1.

50 The disks 2 and 3 are for the purpose of graduating the total amount of air to be

mixed with the carbureted gas, for which purpose they are provided with a number of perforations, in exactly the same relative position in both disks. These holes may be 50 made to register exactly with each other, or to be partially staggered, for which purpose they are fastened together by the screws 16 and 17 which are screwed into the disk 2 and pass through slots in the disk 3, which permits of a partial rotary movement of the disk 3 upon the disk 2, equal to the diameter of the largest perforations in both disks, obtaining by this means a very minute adjustment of the air passages formed by said perforations of the disks 2 and 3.

The wing valve or "butterfly" 1 (see Fig. 3) is for the object of graduating progressively the admission of air, being operated by a crank 7 which is attached to the accelerator rod 14. The butterfly 1 in its initial position stops the holes in the disks 2 and 3, and as it is turned on being acted upon by the accelerator rod, the holes are gradually uncovered until, at the completion of ninety 80 degrees of said movement, they are left entirely uncovered, so that during such movement the air will have been given a perfectly graduated progressive admission to the explosive mixture. The butterfly 1 is pressed 85 against the disk 2 by the action of the spring 19, thus forming an hermetical joint.

Figure 2 represents the apparatus placed in position on the intake pipe of a motor, in front elevation, and in this figure there is 90 shown the connection of the crank 7 to the accelerator rod 14 by means of the link 11, one end of which may be changed from one to another of the holes provided in said crank, increasing or diminishing the lever- 95 age according to the desired length of travel of the rod 14.

The other end of the rod 11 is connected to the rod 14 by means of the two clips 13 provided with convenient screws and the 100 universal joint 12. In arranging the valve for operation, the casing is first taken apart, the valve 3 properly adjusted, and the device is then reassembled.

By the foregoing it will be seen that the 105 invention consists of the form of construction of an apparatus for providing an additional admission of air into the carbureted gas used as the explosive mixture in explosion engines, by means of perforated 110 disks operated by the accelerator.

It will be also clearly understood that

while the relative position and sizes of the said holes as shown in the drawings, constitutes an efficiently operating example of the invention, the latter is not strictly limited 5 to the especial arrangement shown, since it will be possible for any one skilled in the art to vary the position and sizes of said holes, as well as many other details of construction, without thereby departing from 10 the spirit of the invention as set forth in the following claims.

Having thus described my invention, what I claim and desire to protect by Letters Patent of the United States of America, 15 is:—

1. An apparatus for regulating the air supply used in explosive mixtures in engines, characterized by the combination of a casing having air admission openings, a stationary disk mounted in said casing and provided with air admission openings therethrough, a second disk movable mounted upon the said stationary disk and provided with air admission openings registering with 20 the similar openings in the stationary disk when the movable disk is in a certain position, means to limit the turning movement of said movable disk and to secure the same in adjusted position, a wing or "butterfly" valve rotatably mounted on one of said disks, and arranged to cover and uncover the openings thereof and an operating 25

crank attached to said butterfly, and means of communication between the said casing and the intake pipe of the engine. 35

2. In an apparatus for regulating the air supply for the mixture in explosion engines, the combination of a casing connected to the intake pipe of the engine and having air admission openings through which air may 40 pass freely from the outer atmosphere to the intake pipe, a stationary disk mounted in said casing which impedes the flow of air therethrough, and having holes which permit a limited flow of air therethrough, a 45 movable disk rotatably mounted upon the said stationary disk and provided with holes registering with the holes in said stationary disk when in a certain position and stopping or partially closing said holes in the stationary disk in successive rotary positions of the said movable disk, means to secure said disks together when adjusted, a rotary wing or butterfly valve rotatably mounted on one of the said disks and arranged to cover and 50 uncover the openings thereof, and means to operate said wing or butterfly. 55

Signed at Buenos Aires, Argentine Republic, this twentieth day of December A. D. 1919.

MIGUEL ANGEL QUIROGA.
